UNITED STATES PATENT OFFICE.

DINNEY F. GRIFFEY, OF RED JACKET, WEST VIRGINIA, ASSIGNOR OF ONE-HALF TO
ROBERT N. COX, OF RED JACKET, WEST VIRGINIA.

RAILWAY-SWITCH LOCKING AND OPERATING MEANS.

Application filed October 7, 1926. Serial No. 140,093.

It is the primary object of the present invention to provide new and improved means for normally locking a railway switch in one position or the other, but for releasing the switch and permitting automatic throwing thereof to open or closed position, by means of a train-carried member, and in this connection, attention may be invited to the fact that the word "train" wherever it appears herein, is to be considered as comprehending not only a plurality of cars or coaches connected with each other, but also a single car.

A further object of the invention is to provide manually operated means whereby the switch-locking means may be thrown out of play if desired, permitting throwing of the switch by the usual stand or other desired means.

With the foregoing and minor objects in view, the invention resides in the novel subject matter hereinafter described and claimed, the description being supplemented by the accompanying drawings.

Figs. 1 and 1^a jointly represent a top plan view of a portion of a main track, a siding and a switch, with the invention in operative relation therewith.

Figs. 2 and 2^a jointly give a side elevation of the parts shown in Figs. 1 and 1^a, a portion of Fig. 2 being broken away and in section.

Figs. 3 and 3^a jointly show a longitudinal sectional view on the plane of the lines 3—3 of Fig. 1 and 3^a—3^a of Fig. 1^a.

Fig. 4 is a detail longitudinal section on line 4—4 of Fig. 1.

Fig. 5 is a vertical transverse section on line 5—5 of Fig. 1.

Fig. 6 is a fragmentary side elevation partly broken away and in section.

Fig. 7 is an elevation partly in section of the train-carried shoes and their operating means.

Fig. 8 is a horizontal section on line 8—8 of Fig. 7.

The numerals 9 on the accompanying drawings designate the main track rails, 10 denotes the rails of a siding, 11 has reference to the usual frog and 12 refers to the conventional switch tongues, these tongues being connected by a bridle bar 13 from which an operating rod 14 may lead to a switch stand (not shown).

Disposed under and suitably secured to the

portions of the main track rails 9, toward which the switch tongues 12 extend, are four frames 15, 16, 17 and 18, all disposed in vertical transverse planes and each of substantially U-shape, as shown for instance in Fig. 5. Two similar but wider frames 19 and 20 extend under portions of the main track rails and portions of the siding, these frames being of obtuse-angular form when viewed from top or bottom, as will be clear from Fig. 1^a.

Disposed longitudinally between the main track rails are a number of levers 21, 22, 23 and 24, all fulcrumed on vertical axes 25 to appropriate transverse plates 26, secured to the rails. Two of these plates extend not only under the main track rails 9 but under portions of the switch, and fulcrumed upon one of these two plates is a lever 27 whose fulcrum axis 28 is disposed vertically, said lever 27 being disposed between portions of the siding rails 10. The levers 21, 22 and 23 are pivoted to each other at 30, and one of these pivots connects the lever 23 with the bridle bar 13. The end of this lever opposite the bridle bar, is pivoted at 31 to a transverse link 32, the levers 24 and 27 being pivoted to the ends of this link at 34 and 35 respectively.

The levers 21, 24 and 27, carry wedge-shaped cams 36, 37 and 38 respectively, and these cams are co-operable with additional cams or shoes 39 and 40 carried by the train (see Figs. 7 and 8). The cams 39 and 40 are carried by vertical shafts 41 and 42 respectively, and any desired means such as a gear wheel 43 and racks 44, may be provided to permit the simultaneous lowering of one cam to operative position and raising of the other cam to an inoperative position. Suitable means such as the crank 45, rod 46 and hand lever 47 may be employed for rotating the gear 43 and for holding it in neutral position or in either of its other two positions. When shoe 39 is lowered, regardless of the direction in which the train is traveling along the main track, or whether said train is entering or leaving the siding, said shoe will engage one or another of the cams 36, 37, 38 to effect horizontal swinging of the lever which carries such cam, and as all of the levers so far described are connected for operation in unison, they will all be shifted and it will be seen that the bridle bar 13 will move the switch tongues 12 from one position to the

other. When the shoe 40 is lowered, it will engage one or another of the cams 36, 37, 38 to shift it and the levers in the opposite direction from that above described, thus 5 moving the switch tongues in the opposite direction.

Locking bars 50 and 51 are provided for the levers 21, 24 and 27, the bar 50 being associated only with the lever 21 while the bar 10 51 which is relatively long, co-operates with both levers 24 and 27. These two bars are movably mounted within the frames 16 and 20 respectively and as the details of their mounting, construction and operation are 15 about identical, only those regarding the bar 50 (shown in Figs. 1, 2, 3, 4, 5 and 6, will be given). This bar extends transversely between the track rails 9, under the free end of the lever 21 and is formed with openings 20 52, either one of which may receive a stud 53 which projects downwardly from said lever. When this lever is in one position, the stud is received in one of the openings 52 and when said lever is in its other position, 25 the other opening of course receives said stud. Two pins, bolts or the like 54 are secured to and project downwardly from the ends of the bar 50, said pins or the like being received in openings 55^a in the ends of a 30 transverse bar 56 which has rigid connection with the side members of the frame 16. Coiled compression springs 55 surround these pins or the like between the two bars 50 and 56 and exert their power to normally 35 raise said bar 50 to the operative position disclosed in Figs. 3 and 5. Two depressible rails 56^a however, are connected with the bar 50 to depress and release this bar prior to engagement of one or another of the cams, 40 36, 37, 38 by the shoe 39 or 40. Similar rails 57 are connected with the ends of the locking bar 51, one of these rails 57 being adjacent one of the track rails 9 while the other is at one side of one of the siding rails 10, 45 as seen most clearly in Fig. 1^a.

By an arrangement of longitudinally disposed, vertically swingable levers 58 and 59, and links 60-61, the depressible rails 56^a are connected with the rails 57, so that upon 50 depression of any of these rails, to release one of the locking bars 50-51, the levers 58-59 are so moved as to similarly depress the other rails for the purpose of releasing the other locking bar. Thus, with both locking bars released from engagement with the levers 21, 24 and 27, the co-acting train-carried and track-carried cams may come into 55 play to throw the switch in one direction or the other.

60 The levers 58 are suitably fulcrumed at 63 to the side members of the frame 18. Similarly, the levers 59 are fulcrumed at 64 to the side members of the frame 19, in 65 which connection it may be stated that these frames and all others may be of the general

construction herein disclosed or of any other construction which will be suitable for the purposes intended.

The frame 17 projects laterally beyond the track and is provided with upstanding 70 bearings 65 and with a base portion 66 extending longitudinally of and outwardly spaced from the track. Apertured lugs or ears 67 and 68 rise from this base portion 66, for a purpose to appear. A transverse 75 rock shaft 69 is rotatably mounted in the bearings 65 and in other portions of the frame 17, and at one end is provided with a hand lever 70 having a lost-motion connection 71 therewith. This lever may be 80 locked in engagement with either of the lugs 67-68 and when it is engaged with lug 68 as shown in most views, automatic throwing of the switch can be effected and said switch will, upon passage of the train, be 85 locked in the position at which it is left. Provision is made however whereby swinging of the lever 70 and locking it in engagement with the lug 67, will simultaneously de- 90 press and release both locking bars 50 and 51, so that the rod 14 and the switch stand may be used to throw the switch if desired. As will be clear from Fig. 6, throwing of lever 70 to the position shown in this view, will bring the lost-motion connection 71 into 95 play, so that further downward swinging of the lever will turn the rock shaft 69. This shaft is provided with a crank arm 72 linked at 73 to a longitudinal lever 74, the latter being fulcrumed upon a shaft 75 carried by the frame 15. By a suitable connection 76, lever 74 is connected with the locking bar 50. Thus, upon swinging of the lever 70 into engagement with the lug 67 and consequent rotation of the shaft 69, the connections 72, 73, 74, 76 come into play to 100 depress and release the locking bar 50 and due to the arrangement of levers previously described, the locking bar 51 is simultaneously depressed and released. Thus, the 105 levers 21, 24 and 27 are free of the locking bars and the switch may be thrown by means of the stand or otherwise.

It will be seen from the foregoing that 110 while the invention is comparatively simple and inexpensive, it will possess a number of advantageous characteristics. On account of the results obtainable from the details disclosed, they are preferably followed. However, within the scope of the invention 115 as claimed, numerous variations may be made.

I claim:—

1. A mechanism of the class described 120 comprising a train-actuated switch-throwing member between the track rails and shiftable toward and from the same, a locking member for said switch-throwing member mounted for vertical movement and extending under the latter, yieldable means for 125

normally sustaining said locking member in a raised position in which it engages and locks said switch-throwing member, and a train-depressed rail connected with said locking member to depress and release the latter, permitting the train to shift the switch-throwing member.

2. A mechanism of the class described comprising a train-actuated switch-throwing member between the track rails and shiftable toward and from the same, a locking bar under said switch-throwing member extending transversely between the track rails, a frame under the rails having a transverse stationary bar under said locking bar, vertical guide pins projecting from one of said bars and slidably connected with the other bar, coiled compression springs surrounding said pins to normally support said locking bar in a raised position in which it engages said switch-throwing member, and a train-depressed rail connected with said locking bar to depress and release the latter from the switch-throwing member permitting the train to shift the latter.

3. In combination with a main track and a siding including the usual switch tongues; horizontally shiftable switch-throwing shoes between the rails of the main track and siding in position to be engaged by train-carried means regardless of the direction of travel on the main track or whether the train is entering or leaving the siding, a plurality of horizontally swingable levers disposed longitudinally between the rails and operatively connected with each other, certain of said levers carrying said shoes whereby movement of any shoe will cause similar movement of the others, and means connecting one of said levers with the switch tongues whereby shifting of the levers by any of said shoes will move the switch tongues from one position to the other.

4. In combination with a main track and a siding including the usual switch tongues; horizontally shiftable switch-throwing shoes between the rails of the main track and siding in position to be engaged by train-carried means regardless of the direction of travel on the main track or whether the train is entering or leaving the siding, a plurality of horizontally swingable levers disposed longitudinally between the rails and operatively connected with each other, certain of said levers carrying said shoes whereby movement of any shoe will cause similar movement of the others, means connecting one of said levers with the switch tongues, whereby shifting of the levers by any of said shoes will move the switch tongues from one posi-

tion to the other; a plurality of vertically movable locking members normally raised into engagement with said shoes and locking them against movement, train-depressed means connected with said locking members for depressing them to released position, and a plurality of vertically swingable levers disposed longitudinally of the rails and connected with each other and with said locking members, whereby depression of any locking member will depress the other locking members through the instrumentality of said vertically swingable levers.

5. A mechanism of the class described comprising a plurality of train-actuated switch-throwing members, a plurality of vertically movable locking members normally raised into engagement with said switch-throwing members and locking them against movement, train-depressed means connected with said locking members for depressing them to released position, and a plurality of vertically swingable levers disposed longitudinally of the rails and connected with each other and with said locking members, whereby depression of any locking member will depress the other locking member through the instrumentality of said vertically swingable levers.

6. A mechanism of the class described comprising a train-actuated switch-throwing member, a movably mounted locking member for said switch-throwing member, yieldable means for normally holding said locking member in operative position in which it engages said switch-throwing member, train-actuated means connected with said locking member for releasing the same, permitting the train to shift the switch-throwing member, a hand lever operatively connected with said locking member for moving the same to released position when desired, and means for holding said hand lever in the position which it occupies when said locking member is released, whereby to hold said locking member in its released position.

7. A structure as specified in claim 1; together with a rock shaft operatively connected with said locking member for depressing the latter to released position when turned in one direction, a hand lever having a lost-motion connection with said rock shaft for turning it in said direction, and means for holding said hand lever in the position which it occupies when said locking member is released, whereby to hold said locking member in its released position.

In testimony whereof I have hereunto affixed my signature

DINNEY F. GRIFFEY.
